Primary Examiner — Cynthia Ramirez*(74) Attorney, Agent, or Firm* — Shoemaker and Mattare(57) **CLAIM**

The ornamental design for a waste bin with pivot lid opener, as shown and described.

DESCRIPTION

FIG. 1 is a perspective view of a waste bin with pivot lid opener, showing my new design from the top, front and left side;

FIG. 2 is a top plan view thereof;

FIG. 3 is a front elevational view thereof;

FIG. 4 is a view like FIG. 3, showing the lid of the bin partially open;

FIG. 5 is a view like FIG. 3, showing the lid fully open;

FIG. 6 is a left side elevational view thereof;

FIG. 7 is a view like FIG. 6, showing the lid of the bin partially open;

FIG. 8 is a view like FIG. 6, showing the lid fully open;

FIG. 9 is a bottom plan view thereof;

FIG. 10 is a perspective view thereof, from the rear, bottom and right side;

FIG. 11 is a perspective view thereof, from the front, bottom and right side; and,

FIG. 12 is a perspective view thereof, from the rear, bottom and right side.
